SPEED-CHANGE GEARING.

1,195,206.

Specification of Letters Patent. Patented Aug. 22, 1916.

Application filed June 1, 1910. Serial No. 564,381.

To all whom it may concern:

Be it known that I, LELAND F. GOODSPED, a citizen of the United States, and a resident of Milwaukee, in the county of Milwaukee and State of Wisconsin, have made a new and useful Invention in Speed-Change Gearing, of which the following is a specification.

This invention relates to power transmission mechanism and more particularly to change speed mechanism for use in motor vehicles.

In a co-pending application for United States Letters Patent, Serial No. 460,075, I have illustrated and described a change speed mechanism, and the present invention has particularly to do with the operating and controlling device for such mechanism; an object being to produce a single hand lever operated device for controlling and operating the change speed mechanism of said application. This, as well as other objects which will readily appear to those skilled in this art, I attain by means of the device described in the specification and illustrated in the drawings accompanying the same and forming a part of this application and throughout which like elements are denoted by like characters.

In the drawings, Figure 1 is a longitudinal sectional view of a change speed mechanism with which this invention is capable of being utilized. Figs. 2 and 3 are detailed views of portions of the device shown in Fig. 1. Fig. 4 is a detailed view of a portion of the reversing gears of the device shown in Fig. 1. Fig. 5 is a detailed view of one of the jaw clutch operating devices of the device of Fig. 1. Fig. 6 is a view in elevation of the single lever controlling and operating device of this invention. As shown the jaw clutches of the change speed device are in the ahead position and the hand lever in neutral position. Fig. 7 is a view similar to Fig. 6 but as illustrated, the jaw clutches are in the reverse position while the hand lever is shown in the low speed position. Figs. 8 and 9 are detail views of a modification of a portion of this invention.

As this invention consists more or less in the combination of a specific form of change speed device and the controlling and operating mechanism therefor, it is believed that a description of the change speed device

will be of benefit in describing the entire combination. The change speed device consists of a casing 10 within which two axially aligned shafts 11 and 12 are journaled in bearings 13, 14 and 15 and which are adapted to be connected together by means of a friction disk clutch device to form a through shaft. The change speed device includes, besides the direct or high speed drive, an intermediate speed device, a low speed device and a reversing device for utilizing either the intermediate or the low speed devices for driving shaft 11 in the opposite direction from shaft 12. Shaft 12, which I will term the driving shaft, can either be the engine shaft or a shaft positively connected thereto or connected thereto by means of a friction clutch device. Shaft 11 I term a driven shaft and this will be connected in any suitable manner by means of differential gearing to the driving wheels of the vehicle. The friction clutch for directly connecting shafts 11 and 12 is housed within a casing 16 preferably formed integral with shaft 12 and said housing carries a ball bearing 17 for the end of shaft 11. The high speed friction clutch includes annular metallic casing plates 18 which are positively connected by means of projections 19 to casing or housing 16 and consequently revolve therewith. These plates 18 alternate with shaft plates 20 feathered to a hub portion 21, keyed at 22 to shaft 11. A pressure plate 23 which is caused to rotate with housing 16 is movable longitudinally of hub 21 so as to apply pressure to the interleaving plates 18 and 19 by means of pressure pins 24 and actuating levers 25 which are pivoted at 26 to the end plate of the housing.

The intermediate speed device contains a friction clutch similar to the one just described but instead of having the last plate 18 abutting against housing 16, a stop plate 27 is provided which abuts against shoulders formed in housing 16 as shown in Fig. 3 and is caused to rotate with said housing. The shaft plates of the intermediate friction clutch are feathered to a hub portion 28 keyed to telescoping shaft 29 at 30. Telescoping shaft 29 surrounds shaft 11, is journaled in suitable ball bearings 31 and 32, and is provided with a gear 33. This friction clutch device for the intermediate gear device is operated by means of a pressure

plate 34, pressure pins 35, and pivoted levers 36.

The low speed gear device is provided with a stop plate 37 (see Fig. 2) which forms an abutment for the interleaving disks of the low speed clutch which are adapted to be forced together by means of pressure plate 38 and pressure pins 39 and pivoted levers 40. The shaft or loose disks of the low speed device, are feathered to a hub member 41 which is keyed to a telescoping sleeve 42 at 43. The sleeve 42 is provided with a gear member 44. Slidably mounted on sleeve 42 is a clutch actuating member 45 provided with an inclined face 46 and a straight cylindrical face 47. By means of a collar 48, pins 49 projecting therefrom, bell crank lever 50 and actuating rod 51, actuating member 45 is adapted to be slid along sleeve 42.

The long arms of levers 40, 36 and 25 are of different lengths so that as actuating member 45 is slid or moved in a direction away from the clutch device, the levers 40, 36 and 25 are moved in succession, by means of inclined surface 46, to operate the pressure pins 39, 35 and 24, thus operating the low intermediate and high speed clutches in succession and in the order given. A shaft 52 journaled in suitable bearings 53 and 54 has a gear 55 keyed thereto and which meshes with a gear 56 loosely mounted on shaft 11. Shaft 52 also carries two gears 57 and 58 which mesh with gears 44 and 33 respectively and which connect with said shaft 52 by means of suitable overrunning ratchet devices constructed so that when intermediate gear 33 is connected to housing 16 through the intermediate friction clutch device, shaft 52 will overrun gear 57. A jaw clutch member 59 feathered to shaft 11 or mounted on a squared portion thereof as illustrated, is provided with teeth or jaws 60 and 61 on its opposite faces and is adapted to be moved to different positions on shaft 11 by means of a shaft 62 and the connecting mechanism illustrated in Fig. 5. Gear 56 which is loosely mounted on shaft 11 is provided with teeth or jaws 63 with which teeth 61 are adapted to engage when member 59 is moved to one limit of its travel. When jaw clutch member 59 is in what may be termed ahead position; that is, when it locks gear 56 to shaft 11, it will be seen that shaft 11 may either be driven through the low speed device consisting of the low speed friction clutch and gears 44, 57, 55, and 56 or the intermediate set consisting of the intermediate friction clutch and gears 33, 58, 55 and 56, or, shaft 11 may be driven from shaft 12 direct through the high speed friction clutch. In the latter case shaft 52 will be driven by gear 55 and will overrun gears 57 and 58.

The reversing gears of the device consist

of a gear 64 loosely mounted on shaft 52, gear 65 loosely mounted on shaft 11, and an idler gear 66 mounted on a short shaft 67 projecting inwardly from one end of casing 10. A jaw clutch member 68 feathered to shaft 52 or mounted on a squared portion thereof as illustrated, is provided with teeth 69 on one face thereof and these are adapted to engage with teeth 70 formed in one end of gear 64. When it is desired to drive shaft 11 in the reverse direction from shaft 12, gear 65 is connected to shaft 11 by means of jaw clutch device 59 and gear 64 is connected to shaft 52 by means of jaw clutch device 68. In this way through the medium of the idler gear 66, shaft 11 may be driven by means of either the low or intermediate clutch and gearing devices in the reverse direction from shaft 12.

The controlling device.—As before stated, an object of this invention has been to produce a device for controlling and operating the clutch and gearing change speed device above described which may be worked by means of a single hand lever for throwing the ahead gear devices into low, intermediate and high positions and the reverse gear devices into low and intermediate positions. The three plate clutches are operated by means of a hand lever 72 to which their operating sleeve 45 is connected through bell crank lever 50 by means of a rod 51 connected to one arm of said bell crank lever by a ball and socket joint 73 and a lever arm 74 connected to rod 51 and keyed to a rocking rod 75 to which hand lever 72 is also keyed. A sector 76 for lever 72 is provided with low, intermediate and high notches, as indicated in Figs. 6 and 7, and also with a neutral notch 77 and a depressed portion or enlarged notch 78. Lever 72 is provided with a latch 79 which is yieldingly held in contact with the top of sector 76 by means of a spring 80 in the handle of said lever which operates through the medium of rod 81 and pivoted lever 82. Loosely mounted on rod 75 and alongside of sector 76 is a jaw clutch operating lever 83. Jaw clutch member 59 as above stated, is shifted to its different positions by means of the elements illustrated in Fig. 5. These consist of the rotatable rod 62, the arms 84 which are secured thereto and which embrace pins 85 formed upon a slip ring 86 which rides in a channel provided therefor in the periphery of jaw clutch member 59. A short lever 87 is secured to the outer end of rod 62.

A device in all respects similar to the device illustrated in Fig. 5 connects jaw clutch member 68 with a rocking rod 88 to the outer end of which a short lever 89 is secured. Levers 87 and 89 are connected to the lower end of lever 83 in the following manner: Connecting rod 90 connected to the lower end of lever 83 by means of a link 91

and a double bell crank lever 92 is reciprocal-
5 ble within a guide 93. This connecting rod
90 carries a pivotally mounted equalizing
lever 94 to the opposite ends of which levers
87 and 89 are connected by means of links
95 and 96. The upper end of lever 83 is
10 provided with a notch 97, and latch 79 is
provided with an extension 98 which at times
is adapted to lie within notch 97 and by
means of which lever 83 is adapted to be
moved by hand lever 72.

Operation.—The change speed device
15 illustrated in Fig. 1 is shown in neutral position; that is, the friction clutches as well as
the jaw clutch devices are shown in neutral
position. In Fig. 6 lever 83 and the links
and levers connected therewith are shown in
the position they would be with the jaw
20 clutch devices in the ahead or forward position,
the friction clutches being in neutral position.
In Fig. 7 lever 83 and the links and levers
connected therewith are shown as they would be
when the jaw clutch devices are in the reverse
25 position. The hand lever 72 is shown in the position it would be in if the low friction clutch were transmitting
power. The links and levers are so proportioned
and adjusted that it is possible to move lever 83 by means of hand lever 72
30 from the forward position shown in Fig. 6
to the reverse position shown in Fig. 7 without
in any way affecting the friction clutches.
This renders it unnecessary to have a neutral
35 position for the lever 83 because hand
lever 72 so far as the friction clutches are
concerned, can be utilized for moving lever
83 to its different positions without affecting
the operation of any of the friction clutch
40 devices. In practice, assuming that the de-
vice is set as shown in Fig. 6 and it is desired
to operate the vehicle forward, the hand le-
ver will be moved forward into first the low
then the intermediate, and then the high
45 speed notch according to the speed at which
it is desired to drive the vehicle. If it is
moved into the high speed notch, it of course
must be moved through first the low and
then the intermediate in succession. If while
50 it is in the high speed notch it is desired to
drive the vehicle in the reverse direction, the
hand lever 72 will be moved to the rear until
latch 98 rides into notch 97 then hand lever
72 will be moved forward carrying lever 83
55 with it to the position shown in Fig. 7. By
raising latch 98 lever 72 may be disengaged
from lever 83 and either the low or inter-
mediate speed friction clutch device may be
thrown into operation and the vehicle driven
60 in the reverse direction at either the low or
intermediate speed. The high speed clutch
device is not available for use with the re-
versing mechanism for the obvious reason
that when the high speed friction clutch is
65 in operation, shafts 11 and 12 are connected
together to form a through shaft.

If in practice the device is in the position
70 shown in Fig. 7 and it is desired to operate
the vehicle in the forward direction at the
high speed it will be necessary to first move
hand lever 72 to the limit of its travel in the
75 rear direction. This will carry the top of
lever 83 to the rear and when latch 98 has
been disengaged from notch 97 hand lever
72 may again be moved forward past the
low, intermediate and into the high speed
notch. The low and intermediate clutches
will be thrown in in succession and then
80 shafts 11 and 12 connected directly through
the high speed clutch device. Equalizer link
94 allows jaw clutch members 59 and 68 to
either move together or allows one to lag be-
hind the other in their movements. An ar-
rangement such as this is preferable as the
clutch devices are positive.

In Figs. 8 and 9 I have shown a modifica-
85 tion which allows a single lever to be substi-
tuted for the two levers 87 and 89 and this
does away with the necessity for the connect-
ing rod 90, bell crank 92, guide 93, equaliz-
ing link 94, links 95 and 96 and it is neces-
90 sary only to connect lever 83 to lever 87^a by
a connecting rod 91. In this modification
the jaw clutches are arranged so that in
moving to the reverse position the jaw clutch
on shaft 52 will move into contact just prior
95 to the jaw clutch on shaft 11. When chang-
ing from this position again to the ahead po-
sition the clutch on shaft 11 will move out
of contact prior to the clutch on shaft 52.
This allows both of these clutches to be 100
shifted by means of one rock shaft 62^a and
one lever 87^a. The two clutches are arranged
so that in moving into the forward or ahead
position the clutch on shaft 11 will not move
into contact with its coöperating portion un-
105 til the clutch on shaft 52 has moved out of
contact with its coöperating portion of the
reverse mechanism.

Having thus described my invention, what
I claim as new and useful and desire to se-
110 cure by Letters Patent is:

1. The combination of a driving element,
a driven element, a set of continually mesh-
ing speed change gears, a composite multiple
disk clutch device for controlling the opera-
115 tion of said set of gears and for connecting
said driving and driven elements, and a
single actuating device arranged to success-
ively operate or set the different portions of
said clutch device.

2. The combination of a driving element,
a driven element, a set of speed change gears,
a composite multiple disk friction clutch de-
vice for controlling the operation of said set
of gears and for connecting said driving and
driven elements and a single actuating de-
125 vice arranged to successively operate or set
different portions of said clutch device.

3. The combination of a driving element,
a driven element, a set of speed change gears
130

- provided with overrunning devices, a composite clutch device for controlling the operation of said set of gears consisting of a plurality of independent superposed multiple disk clutches and a single actuating device arranged to successively operate said clutches. 5
4. The combination of a driving element, a driven element, continually meshing speed change gears, a plurality of independent superposed multiple disk friction clutches for controlling the operation of said speed change gears and for connecting said driving and driven elements through said gears 10 and means for successively operating said clutches. 15
5. The combination of a driving element, a driven element, a multiple disk friction clutch device for directly connecting said elements, a set of speed change gears, a composite multiple disk friction clutch device superposed on said other clutch device for controlling the operation of said speed change gears and for connecting said driving and driven elements through said gears 20 and a single actuating device arranged to successively operate or set all of said clutch devices. 25
6. The combination of a driving element, a driven element; a friction clutch for directly connecting said elements, speed change gears, a plurality of friction clutches superposed on said other clutch for controlling the operation of said speed change gears 30 and for connecting said driving and driven elements through said gears, reversing gears between said speed change gears and the driven element for reversing the direction of rotation of the driven element, and means 35 for operating said clutches. 40
7. The combination of a driving element, a driven element, continually meshing speed change gears, a plurality of superimposed multiple disk friction clutches one of which is adapted to directly connect said driving and driven elements while the others are adapted to control the operation of said speed change gears and to connect said driving and driven elements through said gears, 45 a single actuating device arranged to successively operate or set said clutches and reversing gears between the speed change gears and the driven element for reversing the direction of rotation of the driven element. 50
8. The combination of a driving element, a driven element, a set of speed change gears, a composite multiple disk clutch device one portion of which is adapted to directly connect said driving and driven elements while the other portions are adapted to control the operation of said speed change gears, telescoping sleeves surrounding said driven element for connecting said driving and driven elements through said 55
- gears and a single actuating device arranged to successively operate or set the different portions of said clutch device. 60
9. A composite clutch device consisting of a plurality of independent superposed multiple friction disk clutches and a single actuating device arranged to successively operate said clutches. 70
10. A composite clutch device consisting of a plurality of superposed multiple friction disk clutches, yielding means for setting said clutches and a single actuating device arranged to actuate said means for successively operating or setting said clutches. 75
11. The combination of a driving element, a plurality of telescopically arranged driven elements, a plurality of independent multiple disk friction clutch devices for connecting said driving and driven elements, a single actuating device arranged to successively operate or set said clutch devices, and means adapted to be driven by said driven elements. 80
12. The combination of a driving element, a plurality of driven elements, a plurality of superposed independent multiple disk friction clutches for connecting said driving and driven elements, a single actuating device arranged to successively operate or set said clutches, and means driven by said driven elements. 85
13. The combination of a driving element, a plurality of driven elements, a plurality of superposed independent multiple disk friction clutches for connecting said driving and driven elements, a power delivery shaft, speed change gears between said driven elements and said shaft, overrunning devices associated with said gears, and a single actuating device arranged to successively operate or set said clutches. 90
14. The combination of a driving element, a plurality of telescoping driven elements axially aligned therewith, a plurality of independent multiple disk friction clutches for connecting said driving and driven elements, a power delivery shaft, speed change gears between said driven elements and said shaft, overrunning devices associated with said speed change gears, means for successively operating or setting said clutches, and reversing gears between said driven elements and said driven shaft for causing the shaft to be driven in a direction opposite to the driving shaft. 110
15. The combination of a driving element, a power delivery shaft, a multiple disk friction clutch for directly connecting said element and said shaft, a plurality of driven shafts telescopically arranged with relation to said power delivery shaft, speed change gears between said driven shafts and said power delivery shaft, a multiple disk friction clutch device for each of said driven shafts superposed upon the clutch for di- 120
- 130

rectly connecting said driving element and said power delivery shaft, means for rotating said power delivery shaft in the opposite direction from said driven shafts, and 5 a single actuating device arranged to successively operate said clutches.

16. The combination of a driving shaft carrying an enlarged end, a power delivery shaft, one end of which is journaled in a bearing carried in said enlarged end, a plurality of driven shafts telescopically arranged with relation to said power delivery shaft, a multiple disk friction clutch device for directly connecting said driving shaft 10 and said power delivery shaft, a multiple disk friction clutch device for each of said driven shafts, means for successively operating said clutches, gearing between said driven shafts and said power delivery shaft 15 whereby said power delivery shaft may be driven in the same direction as said driven shafts but at different speeds, means utilizing said gearing for driving said power delivery shaft in the opposite direction to 20 said driven shafts and overrunning devices associated with said gearing.

17. The combination of a multiple speed ahead and reverse gearing device, a composite clutch mechanism for controlling the 30 operation of said device, a pivoted lever the position of which determines whether said device is to operate for ahead or reverse and a second lever for operating said first lever and for actuating said clutch mechanism.

18. The combination of a driving shaft, a power delivery shaft, a friction clutch for directly connecting said shafts, a multiple speed gearing device, a plurality of friction

clutches for controlling the operation of said gearing device, reversing means, clutches associated with said reversing means and said gearing device, the position of which determines the direction of rotation of said power delivery shaft with relation to said driving shaft and means for successively operating 40 said friction clutches.

19. The combination of a driving element, a driven element, a set of continually meshing gears, a plurality of independent superimposed multiple disk clutch devices 50 for controlling the operation of said set of gears and for connecting said driving and driven elements, and a single actuating device for successively operating said clutch devices.

20. In combination with a driving shaft and a driven shaft, a plurality of driven elements between said shafts, speed change gears and reversing gears between said elements and said driven shaft, independent 60 clutch devices between said driving shaft and said elements, clutch mechanisms for connecting said speed change gears or said reversing gears to said driven shaft, a single lever for setting the separate clutch devices, 65 and means carried by the lever for rendering one or the other of said clutch mechanisms operative.

In testimony whereof, I have hereunto subscribed my name this 28th day of May, 70 1910.
